US0D1097383S

(12) **United States Design Patent** (10) Patent No.: **US D1,097,383 S**
(45) Date of Patent: ** Oct. 7, 2025

(54) **ULTRASONIC BARKING RESTRAINING DEVICE**

(71) Applicant: **Hui Liu**, Guangdong (CN)

(72) Inventor: **Hui Liu**, Guangdong (CN)

(**) Term: **15 Years**

(21) Appl. No.: **29/959,060**

(22) Filed: **Aug. 23, 2024**

(51) LOC (15) Cl. **30-99**

(52) U.S. Cl.

USPC **D30/199; D10/104.1**

(58) **Field of Classification Search**

USPC ..... Primary Examiner — Susan Moon Lee

CLAIM

The ornamental design for a ultrasonic barking restraining device, as shown and described.

DESCRIPTION

FIG. 1 is a front, right, and top perspective view of a ultrasonic barking restraining device showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the ultrasonic barking restraining device that form no part of the claimed design.
